UNITED STATES PATENT OFFICE.

ARTHUR JAMES ROBINSON, OF SHERIDAN, WYOMING, ASSIGNOR OF ONE-FOURTH TO ARTHUR BULLOCK, ONE-FOURTH TO JAMES A. THOMPSON, AND ONE-FOURTH TO THOMAS LEECH, ALL OF SHERIDAN, WYOMING, AND ONE-EIGHTH TO RICHARD WILLIAMS AND ONE-EIGHTH TO CHARLES GRIMM, BOTH OF GREER, IDAHO.

AMALGAMATOR.

1,121,537.

Specification of Letters Patent. Patented Dec. 15, 1914.

Application filed November 22, 1913. Serial No. 802,431.

To all whom it may concern:

Be it known that I, ARTHUR J. ROBINSON, a citizen of the United States, and a resident of Sheridan, in the county of Sheridan and State of Wyoming, have invented a new and Improved Amalgamator, of which the following is a full, clear, and exact description.

My invention relates to an amalgamator in which the sand or pulverized rock is fed to a standpipe from a hopper, and escapes laterally at the base of the pipe through a body of quicksilver. I provide means within the standpipe to agitate the sand and to force its passage through the quicksilver, after which the sand is subjected to washing before being permitted to escape from the apparatus.

The object of my invention is to provide an amalgamator improved in various particulars, to the end that efficiency in operation may be promoted, as well as simplicity of construction and control.

The invention consists in the novel features hereinafter described and claimed.

Reference is to be had to the accompanying drawings forming a part of this specification, in which similar characters of reference indicate corresponding parts in all the views.

Figure 1 is a vertical section of an amalgamator constructed in accordance with my invention; Fig. 2 is a horizontal section on the line 2—2 of Fig. 1; and Fig. 3 is a detail horizontal section on the line 3—3 of Fig. 1.

In constructing the illustrated embodiment of my invention, a suitable base 10 is provided and any approved framework 11 is erected thereon. A standpipe 12 is provided having a side inlet 12^a, into which material in the way of sand or pulverized rock is fed from a hopper 13. The lower end of the standpipe sets in a pot or shell 15, and in practice, a body of quicksilver 16 is contained in the said shell and in the lower end of the standpipe, through which the sand is forced, as hereinafter described. The shell has a flaring upper end 15^a, and the upper edge is below a trough 17, into which the sand escapes, to finally tail off through a spout 18 on said trough.

Disposed axially in the standpipe 12 is a

shaft 19, having suitable bearings, here shown as consisting of a stepped bearing 20, 55 an intermediate sleeve bearing 20^a formed on a bracket 20^b secured to the interior of the pipe 12, and an upper flanged bearing 20^c in the form of a bushing, ball bearings 21 being provided between the flanged bearing and a miter pinion 22 secured to the upper end of the shaft. Meshing with the pinion 22 is a bevel pinion 23 on a drive shaft 24 turning in suitable bearings 25 driven in any suitable manner as by a pulley 65 26, which in practice, will be belted to any convenient source of power. Any other suitable means may be employed for turning the shaft 19.

In order to force the sand downwardly 70 through the body of quicksilver within the tube 12, and cause it to rise through the quicksilver at the extremity of the tube, a spiral blade 27 is secured to the shaft and given preferably but a single convolution, 75 and there is provided below the spiral blade a spiral series of lateral agitating fingers 28, these being provided on a head 29 which is secured to the shaft 19, and tapers toward the lower end to allow an increasing clearance for the sand, with a view to prevent the crowding of the latter as it passes through the lateral openings 14. Additional lateral agitating fingers 30 are disposed on the shaft 19, in various positions above the 85 spiral blade 27, which prevent the sand from banking above said blade. An annular lining 12^b is secured to the tube 12 around the blade 27, screws 12^c or other fasteners being employed for the purpose, to permit the removal and renewal of the lining. The lining 12^b has its upper edge beveled in an inward and downward direction to direct the material toward the blades 27 and to prevent clogging by avoiding any abrupt 95 shoulder. Thus the lining will receive the wear of the sand as it is forced downwardly through the quicksilver seal by the blade, and the wearing surface may thus be readily renewed.

Within the flaring upper end 15^a of the shell 15, variously disposed depending nozzles 31 are arranged on branch pipes 32 of a ring pipe 33, which is supported adjacent to the top of the pot 15 by brackets 34 secured to the standpipe 12, said ring pipe

being in communication with a supply pipe 35, adapted in practice to be connected with any convenient water supply. A body of water is maintained in the shell 15 and its flaring portion 15^a, and the water and the sand therein will be agitated by the jets from the various nozzles, whereby the sand will be thoroughly washed and freed from any valuable particles of material adhering to the same, the sand finally flowing with the water over the upper edge of the shell to the trough 17, and passing outward through the spout 18.

It is to be understood that in practice, any approved means will be provided for removing the amalgamated material from the amalgamating pot, there being indicated conventionally in dotted lines, an outlet pipe 36 leading from the pot 15.

20 The apparatus involves a minimum cost for construction and maintenance, and is well adapted for embodiment in apparatus suited for either large or small operators.

Having thus described my invention, I claim as new, and desire to secure by Letters Patent:

1. An amalgamator, comprising a supply pipe adapted to receive the material to be treated, an amalgamating pot surrounding the lower end of the feed pipe and adapted to receive a quicksilver seal for the pipe, said pipe having a discharge opening establishing communication with the pot, a vertical shaft in said pipe, a spiral blade on said shaft to force the material downwardly, a head on the shaft below the blade, the said head tapering toward the lower end, and

laterally projecting agitator fingers on said head.

2. An amalgamator, comprising a supply pipe adapted to receive the material to be treated, an amalgamating pot surrounding the lower end of the feed pipe and adapted to receive a quicksilver seal for the pipe, said pipe having a discharge opening establishing communication with the said pot, a spiral blade on the shaft adapted to force the material downwardly into the pipe and through the seal, a removable annular lining in the pipe around the said blade, said lining having its upper edge beveled in an inward and downward direction, and agitating fingers rigid with the shaft and disposed both above and below the said blade and the lining.

3. In an amalgamating apparatus, an amalgamating pot, means for feeding to the said pot, near the bottom, the material to be treated, a water supply ring adjacent to the top of the pot, a series of nozzles depending from the ring and disposed within the upper portion of the pot at varying heights and at different points around the pot, means for connecting the ring with a water supply, and means for carrying off the water and tailings from the pot.

In testimony whereof I have signed my name to this specification in the presence of two subscribing witnesses.

ARTHUR JAMES ROBINSON.
